UNITED STATES PATENT OFFICE.

FRANK A. BROWN, OF WEST PIKE, PENNSYLVANIA.

DESIGN FOR A FAMILY-RECORD-BOOK LEAF.

No. 38,030.

Specification for Design.

Patented May 22, 1906.

Application filed April 5, 1906. Serial No. 310,183. Term of patent 14 years.

To all whom it may concern:

Be it known that I, FRANK A. BROWN, a citizen of the United States, residing at West Pike, in the county of Potter and State of Pennsylvania, have invented a new, original, and ornamental Design for Family-Record-Book Leaves, of which the following is a specification, reference being had to the accompanying drawing, forming part thereof.

The figure is a face view of a family-record-book leaf, showing my new design.

I claim—

The ornamental design for a family-record-book leaf, as shown.

FRANK A. BROWN.
